UNITED STATES PATENT OFFICE.

FREDERICK C. BILLINGS, OF MIAMI, FLORIDA.

DRYING PAD FOR PIANOS.

Application filed September 16, 1926. Serial No. 135,788.

My invention relates to improvements in drying pads for pianos, and has for its primary object a pad which is designed to be placed in pianos, and especially for preventing moisture from being absorbed by the pin block and the hammer mechanism, thereby preventing the piano from getting out of pitch and also preventing the sticking of the keys.

10 By preventing the accumulation of moisture in the working parts of the piano, these parts are always maintained in the same condition as when they leave the factory and since both the pin block and the major portion 15 of the key mechanism are all constructed of wood, any absorption of moisture by these parts causes swelling. In the pin block, this swelling will in time affect the holes in which the tuning pins are driven and cause 20 the pins to become loosened so that the piano will not hold its pitch. In the key board mechanism the parts are fitted fairly close together and any swelling causes a sticking 25 of the keys and hammers and prevents them from repeating rapidly. In other words, the key will have a sluggish return action and at times this action becomes so sluggish that it is impossible to execute a trill. Also 30 moisture will affect the leathers used in the action causing them to become soggy and stretch, and eventually causing them to rot. There are also numerous springs and pins used in the action, which moisture will cause 35 to rust, thus hindering the ready action thereof and also quickly deteriorating them. Another serious effect that moisture has in 40 piano actions is to affect the polished graphite bearing surfaces causing the action to become sluggish and stick.

45 A still further object of my device is to prevent the accumulation of dust in the action and by its use I am also enabled to employ insecticides, such as moth balls or the like, to preserve the felt on the hammers and to prevent moths from attacking the same.

I have also discovered especially in grand pianos that the open space in which the hammers work acts as a flue drawing in moist air through the spaces between the keys into the action and thence passing it upward. My pad in addition to the advantages pointed out acts the same as a damper in a flue and retards this circulation to a great extent.

50 My device is equally applicable to grand

pianos, uprights, and player pianos, and in the latter not only performs all of the functions aforesaid but in addition protects the delicate parts of the player mechanism, that is it keeps the metallic parts from rusting and it preserves the bellows. In addition to the above features of my device, it is so constructed and arranged that when in position, it will not in any way affect the tone 60 volume or tone quality of the piano and there will be absolutely no rattling due to the vibrations. In fact my device when once in position can remain there indefinitely. In fact it is my intention that the device 65 remain there permanently with the exception that it be removed when the instrument is to be tuned.

I have also found by the use of my device that it prevents rusting of the strings 75 and that a piano, in which it is installed, will remain in tune much longer than the ordinary piano.

My device is especially useful in pianos in climates where there is a great amount of moisture as by its use I have found that I can keep a piano at practically factory conditions throughout the year and the cost of keeping the same in this condition is only at the expenditure of a small amount 80 of electric current, the amount of expenditure being a great deal less than the amount necessary to replace rusty springs and to overhaul the action periodically due to the presence of moisture, and in addition to this, as aforesaid, the pin block is always kept in 85 perfect condition so that when the piano is once tuned, there will be no loosening of the pins in the pin block due to the swelling and contraction caused by the absorption and 90 expulsion of the moisture.

In the drawings:

Fig. 1 is a top plan view of my device;

Fig. 2 is a similar view with the top cover removed;

Fig. 3 is a longitudinal section taken on the line 3—3 of Fig. 2;

Fig. 4 is an enlarged cross section taken on the line 4—4 of Fig. 2 with the flap turned up;

Fig. 5 is a fragmental top plan view of a piano with the music rack removed showing my device in position;

Fig. 6 is a longitudinal view of the forward portion of the same; and

Fig. 7 is a cross section view of an upright piano with my device in position.

In the construction of my device I employ a bottom member 8 which is provided with reticulations or perforations 9. Secured to the bottom member 8 are longitudinally extending loops 10 and 11 and laterally extending loops 12 and 13. The laterally extending loops 12 and 13 are of such length as to abut the edges of the loops 10 and 11. The loops 10 and 11 have stiffening rods 14 passed therethrough, while the loops 12 and 13 have stiffening rods 15 inserted in a similar manner. These stiffening rods may be of various material. They may be wooden dowels. They may be solid rubber strips, or they may be rubber tubes with a metallic core, which core may be either solid or in the form of a spiral spring. The loops 10, 11, 12 and 13 are secured to the bottom member 8 by means of stitching 16. Parallel to the loops 12 and 13 and secured to the bottom 8 by means of stitching 17 are loops 18 and 19. These loops, however, are of less length than the loops 13 so as to provide passageways 20 between one end and the loop 11 and passageways 21 between the opposite end of the loops and the loop 10. The bottom 8 extends forward so as to form a short flap 22 to which are secured portions of a glove or snap fastener 23. The remaining portion of these fasteners is secured to the flap 24 formed integral with the top 25. The top 25 is secured to the bottom 8 adjacent its rear edge by means of stitching 26 and along its sides by means of stitching 27, the stitching 27, however, being so interrupted as to permit the insertion of the stiffening members 14. Secured to the rear of the assembled pad is a flap 28, the purpose of which will be explained in detail later. It is my intention to insert in one of the compartments formed by the loops 18 and 19 and preferably in the center compartment an electric heating pad 29, which is connected by means of electric conductors 30 to any suitable source of electric energy. This electric pad is a commercial article, which may be bought in the open market and is at present used for medicinal purposes to take the place of a hot water bottle and is equipped with means whereby various temperatures may be obtained and since this article can be readily bought in the open market, its precise construction forms no part of my invention and, therefore, will not be described in detail.

Referring to Figs. 5 and 6, 31 represents the case of a grand piano, 32 the key board, and 33 the plate. The plate 33 is provided with ribs 34 which support a forward plate 35 thus leaving a space 36 in which the piano action including the hammers 37 and dampers 38 operate. 39 is one of the tuning pins and 40 one of the strings. When my device is used in a grand piano, it is placed so that it rests on top of the ribs 34 and also

certain other portions of the plate and its securing means not shown, which are common in the construction of all pianos of this type. The front top cover 42 is designed to be folded backward as illustrated 79 and to remain in this position at all times and the flap 28 is turned upward as illustrated in Fig. 6 so as to rest against the edge of the cover 42. In this way it will be seen that the entire open space 36 together 75 with the tuning pins 39 is completely covered over thus eliminating dust and the possibility of any foreign substances falling between the strings and entering the action. In Fig. 7 43 represents the plate, 42 the pin block, 43* one of the strings, 44 a hammer, 45 one of the dampers, and 46 a portion of the case. In the construction of pad used for an upright or a player, the flap 28 is made longer than for a grand piano and hangs 85 downward as illustrated in Fig. 7 so as to be between the piano action or rather hammers and the front of the piano.

It is my intention, of course, that the entire pad be made of fabric such as felt or the like and with the bottom member reticulated although if desired, the bottom member may be made of open mesh material.

The operation of my device is as follows: When the cover or pad is received, the reinforcing rods are left out and sent separate so that the first step will be to slip the reinforcements into their proper loops. The electric heating pad is next placed in position and the flaps 22 and 24 secured together 90 by means of the glove or snap fasteners. The device is then placed in the piano with the reticulated portion downward and the electricity turned on. This heats the pad and in so doing heats the air between the cover and the bottom of the piano pad, and on account of providing the passages 20 and 21 a circulation of air is permitted through the various compartments thereby insuring heated air throughout the pad, the air becoming 105 heated naturally will absorb moisture and this is accomplished by drawing moisture through the reticulations 9. The moisture thus drawn through the reticulations in turn becomes warmed up and passes upward where it is absorbed by the top 25. This top in turn becoming heated from the electric pad and the heated air will dry the moisture from it or rather from its upper surface and therefore in a short time all of the moisture 110 within the piano case or rather that around the action will be thus driven or pumped out and before it has time to be absorbed by any of the working parts of the piano thereby preventing any swelling due to moisture or any corrosion of the metal parts and thus the piano action as well as the pin block is 115 always maintained in a substantially perfect condition.

It will also be noted from Figs. 6 and 7 that 120

no part of the pad is in contact with the strings or any of the working parts and therefore does not in any way affect them. Furthermore when playing a grand piano, the flap 28 is folded down so that it will not interfere with the tone by dampening it. While in the upright practically all of the tone comes out through the back as it is not customary under ordinary conditions to open either the front or top of the same and therefore its volume will not be diminished in any way by the employment of my pad.

My pad is also very valuable in extremely dry climates as I have found that a piano is also effected by extreme dry air. This causes the action to loosen up necessitating all screws to be tightened, the pin block contracts causing the pin holes to widen so that the pins will not hold the tension of the strings. The same also applies to all center pin bearings and the key center of the balance rail and front guide pins, and as the dry air enters the piano similar to the moisture, that is along the spaces between the keys, the circulation of this dry air through the piano is also prevented by the damper effect of the pad. In addition I have discovered that in the extreme north where pianos are in unheated rooms, frost will accumulate on the strings and metal parts and when a room is heated, the frost melts and causes the metal parts to rust.

My device will prevent the accumulation of frost by absorbing the moisture and, on account of the heating pad, which is placed inside of my pad, the piano can be kept dry at all times and without the necessity of expending a large amount of fuel to keep an un-used room in which the piano may be placed warm at all times. In fact it is believed that even without the electric pad, the device will keep the piano dry and prevent the accumulation of frost for the reason that the circulation of cold air through the piano is greatly retarded, if not altogether stopped, by the pad. This also makes my device useful in shipping pianos as the manufacturer can place a pad therein and protect the instrument while in transit, and when moth balls are placed within the pad, the top cover being imperforate will prevent the odor of the moth balls from being diffused throughout the room but at the same time the felt parts of the piano will be protected thereby against the ravages of these pests and in addition to preventing the entrance of trinkets, such as pencils and the like from falling in between the strings and into the action, the entrance of dust is also prevented to a great extent.

In extremely dry temperatures where the action has become loosened on account of shrinkage of the various wooden parts, I may place a damp towel or other cloth in the chamber of my pad thereby restoring mois-

ture to these portions and I have found that within a very short time the action will be restored to normal. In this way windows can always remain open regardless of whether the piano is located in an extremely dry or an extremely damp climate, and any possibility of rust or undue swelling by moisture or shrinkage by extreme dryness is obviated and the piano can always be kept in perfect condition.

Having fully described my invention, what I claim is:—

1. A drying pad for pianos comprising an absorbent member having a spaced apart top and bottom, reinforcing members interposed between the top and bottom for stiffening said pad, and a flap secured to said pad along one of its longitudinal edges. 75 80

2. A drying pad for pianos comprising a member having a spaced apart top and bottom, reinforcing members located between said top and bottom for stiffening said pad, a flap secured to said pad along one of its longitudinal edges, and means for supplying heat between said top and bottom. 85 90

3. A drying pad for pianos comprising a member having a reticulated bottom and a top spaced apart therefrom, reinforcing members removably located between said top and bottom for stiffening said pad, and a flap secured along one longitudinal edge of said pad. 95

4. A drying pad for pianos comprising a member having a reticulated bottom and a top in spaced apart relation to each other, reinforcing members for stiffening said pad, a flap secured to said pad along one of its longitudinal edges, and means for introducing heat within the pad and between said top and bottom. 100 105

5. A drying pad for pianos comprising a member having a reticulated bottom and a top spaced apart from each other, reinforcing members for stiffening said pad, means for dividing said pad into a plurality of communicating chambers, and a flap secured along one of the longitudinal edges of said pad. 110

6. A drying pad for pianos comprising a member having a reticulated bottom and a top spaced apart from each other, reinforcing members for stiffening said pad, means for dividing said pad into a plurality of communicating chambers, a flap secured along one of the longitudinal edges of said pad, 115 120 and means for introducing heat into one of said chambers.

7. A drying pad for pianos rectangular in shape and composed of absorbent material and being of a length substantially the length of the inside of a piano casing, and a flexible flap secured along one of the side margins of said pad, said flap being more flexible than the pad. 125

8. A drying pad for pianos composed of 130

4
fibrous absorbent material being of a size to cover the pin block and hammer and damper action of a piano, and a flexible flap secured along one edge of said pad for restricting the circulation of air over and around said hammer and damper action and the pin block.

9. A drying pad for pianos rectangular in shape and composed of absorbent material and being of a length substantially the length of the inside of a piano casing, a flexible flap secured along one of the side margins of said pad, said flap being more flexible than the pad, and means for stiffening said pad.

10. A drying pad for pianos composed of an upper and a lower layer of absorbent material, said layers being secured together along three edges, reinforcing members extending laterally and longitudinally of said pad for stiffening the same and spacing the layers apart whereby pockets are formed between the layers, means carried by the unse-

cured edges of said layers so that they can be detachably secured together and access had to said pockets, and a flexible flap secured along the edge of said pad opposite said last mentioned edges.

11. A drying pad for pianos composed of an imperforate upper and a perforated lower layer of absorbent material rectangular in shape, said layers being secured together along three edges, reinforcing members extending laterally and longitudinally of said pad for stiffening the same and spacing the layers apart whereby pockets are formed between the layers, means carried by the unsecured edges of said layers so that they can be detachably secured together and access had to said pockets, and a flexible flap secured along the edge of said pad opposite said last mentioned edges.

In testimony whereof I have affixed my signature.

FREDERICK C. BILLINGS.
